UNITED STATES PATENT OFFICE.

CHARLES WM. RIPSCH AND JAMES C. DAWLEY, OF DAYTON, OHIO.

LIFTING-JACK.

1,376,831.

Specification of Letters Patent.

Patented May 3, 1921.

Application filed August 16, 1920. Serial No. 403,818.

To all whom it may concern:

Be it known that we, CHARLES W. RIPSCH and JAMES C. DAWLEY, citizens of the United States, residing at Dayton, in the 5 county of Montgomery and State of Ohio, have invented certain new and useful Improvements in Lifting-Jacks, of which the following is a specification, reference being had therein to the accompanying drawing.

10 This invention relates to lifting jacks and more particularly to a lifting jack of the self lowering type.

The object of the invention is to provide a practical, highly efficient, self lowering 15 jack which will be motor operated.

A further object of the invention is to provide such a jack in which the load may be lowered independently of the motor.

A further object of the invention is to 20 provide such a jack in which the motor must be disconnected from the lifting element before the load can be lowered.

Other objects of the invention will appear as the device is described in detail.

25 In the accompanying drawings Figure 1 is a side elevation, partly in section, of a jack embodying our invention; Fig. 2 is a plan view, partly broken away, of such a jack; Fig. 3 is a side elevation, partly 30 broken away, of such a jack; and Fig. 4 is a detail view, partly in section, of the clutch and brake operating device.

In these drawings we have illustrated one embodiment of our invention and have 35 shown the same as applied to a self lowering jack, the main features of construction and operation of which are well known, but it will be understood that this particular embodiment of the invention has been chosen 40 for the purpose of illustration only and that the invention may take various forms and may be applied to jacks of various kinds without departing from the spirit thereof.

The particular jack here illustrated is 45 similar in its main features and operation to the jack shown and described in Patent No. 1344117, granted June 22, 1920, to Charles W. Ripsch, James C. Dawley and Charles D. Derby, but it will be noted that 50 the mechanism has been inverted so that the operating and controlling devices are mounted on the stationary base instead of traveling with the lifting element. As here 55 illustrated the jack comprises a base 1 having mounted thereon and rigidly secured thereto an upwardly extending hollow

housing 2 in which is mounted a vertically movable lifting member 3. This lifting member is here shown as a hollow standard having at its upper end a cap, or load engaging member, 4 and having at its lower end a nut 5 into which is threaded an actuating screw 6 the lower end of which is rotatably supported on the base 1. This screw is rotated to impart upward movement to the lifting element by means of an operating shaft 7 which is journaled in partitions 8 and 9 in a lateral extension 10 of the housing 2. The operating shaft may be connected with the screw in any suitable manner but, as here shown, a beveled gear 11 is rigidly secured to the lower end of the screw and meshes with a beveled gear 12 rigidly secured to the inner end of the operating shaft 7.

The operating shaft is driven from a motor of any suitable kind but preferably we employ an electric motor, as shown at 13. The motor may be connected with the operating shaft in any suitable manner but we prefer to employ worm gearing as this gives the necessary reduction in speed and is very powerful in its operation. As here shown, a worm gear 14 is mounted on the operating shaft and meshes with a worm 85 15 rigidly secured to a shaft 16 with which the shaft of the motor 13 is directly connected. It is desirable that the motor should be disconnected from the lifting element during the lowering of the load and to this 90 end a clutch may be interposed between the motor and the lifting element. While this clutch may be located at any suitable point we have, in the present construction, arranged it between the worm wheel 14 and the 95 shaft 7. To this end the worm wheel 14 is rotatably mounted on the shaft 7 and has secured thereto one member 17 of the clutch, the other member 18 of which is slidably mounted on the shaft 7 and is held against 100 rotation thereon. The clutch may be controlled in any suitable manner but preferably the member 18 is positively moved into and out of operative engagement with the member 17 thereof and to this end the clutch 105 member 18 is provided with a circumferential groove 19 into which extend pins 20 carried by a yoke 21 mounted on a shaft 22.

The pitch of the screw 6 which actuates the lifting element is such that when unrestrained, the lifting element will move downwardly under the weight of its load.

These controlling devices are here shown as of such a character that they will be connected with the lifting element only during its downward movement and they preferably comprise a worm wheel 23 loosely mounted on the shaft 7 and adapted to be automatically connected therewith when said shaft is rotated in a reverse direction by the downward movement of the lifting element. To this end the worm wheel carries one member 24 of a clutch, the other member 25 of which is slidably mounted on the shaft 7, held against rotation relatively thereto, and pressed toward the first mentioned clutch member 24 by means of springs, one of which is shown at 26. The clutch members are provided with ratchet teeth so that when the shaft is rotated in a forward direction, that is the direction in which it is rotated to lift the load, the teeth of the clutch member 25 ride over the teeth of the clutch member 24 and if the shaft 7 is rotated in the opposite direction the teeth of the clutch members will be brought into operative engagement to rigidly connect the worm wheel to the shaft. The worm gear 23 meshes with a worm 27 rotatably mounted on a shaft 28 extending at right angles to the shaft 7 and the pitch of the spirals of the worm and worm gear is such that the worm will be rotated by the worm wheel. Connected with the worm 27 for rotation therewith, and preferably mounted on the shaft 28, is a second worm wheel 29 which meshes with a second worm 30 rigidly secured to a shaft 31, the pitch of the spirals on the worm gear 29 and the worm 30 being also such that the worm will be rotated by the worm gear. Connected with the worm 30 is a suitable device for controlling the rotation thereof, which is preferably in the form of a brake. Inasmuch as the worm gearing will absorb, to a very large degree, the power, or thrust, exerted upon the shaft 7 by the downward movement of the load, a very light braking action will serve to control the movement of the worm 30 and, consequently, of the load. As here shown, the brake comprises a drum 32 rigidly secured to the shaft 31 and adapted to be rotated at a relatively high speed by that shaft, due to the speed multiplying action of the worm gearing. Coöoperating with the brake drum are two brake shoes 33 which are provided with intersecting arms 34 which are moved one toward the other, to cause the brake shoes to frictionally engage the brake drum, by a spring 35. Consequently, the brake acts normally to hold the controlling devices against movement and hence to lock the load against downward movement. Suitable means are provided for separating the arms 34 and to thus move the brake shoes out of engagement with the brake drum 65 and to release the load. As here shown, this

is accomplished by inserting between the ends of the arms 34 a cam shaped operating member 36 which is carried by, and preferably formed integral with, a stud 37 journaled in the wall of the casing 10 and having on its outer end an operating lever, or finger piece, 38 by means of which it may be rotated to cause the cam 36 to separate the arms 34 against the tension of the spring 35. 70

It is desirable that the motor should be disconnected from the operating shaft before the latter is rotated in a reverse direction by the downward movement of the load, and the present construction is such that the motor must be disconnected from the shaft before the load can begin its downward movement. To accomplish this we have provided a single actuating device for operating the clutch, 17-18, and the cam 36 and the construction is such that the clutch 85 will be actuated to disconnect the motor before the brake is manipulated to release the load. In the present construction this is accomplished by providing the stud 37, which carries the cam 36, with a rock arm 90 39 which is connected by a link 40 with the yoke 21 of the clutch, so that this clutch will be actuated upon each operation of the lever 38. To cause the clutch to be operated before the brake is released the cam 95 36 is of such a character that there will be sufficient clearance between the same and the arms 34 of the brake to permit the clutch to be disengaged before the cam operatively engages the arms. As shown in full lines 100 in Fig. 4, the cam is out of engagement with the brake arms 34, its flat sides being spaced appreciable distances from the respective arms. As shown in dotted lines the cam has been rotated a sufficient distance to cause 105 the clutch 17-18 to be operated to disconnect the motor from the shaft and the cam has just engaged the arms 34, so that the further movement thereof will separate these arms and release the brake. 110

The operation of the mechanism will be readily understood from the foregoing description of the several parts thereof and it will be apparent that we have provided a lifting jack in which the lifting element 115 is elevated by power derived from a motor and in which the lifting element and its load may be lowered by gravity independently of the motor, the motor being disconnected from the lifting element during the 120 lowering operation. It will further be apparent that we have provided means for controlling the downward movement of the load, independently of the motor, and that this means is of such a character that its 125 manipulation to permit the downward movement of the load will cause the motor to be disconnected from the lifting element before the latter begins its downward movement. Further, it will be apparent that 130

the mechanism is simple in character, and of a strong, durable construction which is well adapted to the handling of heavy loads for which the jack is designed, jacks of this 5 type being designed for loads up to fifty and seventy-five tons.

While we have shown and described one embodiment of our invention we wish it to be understood that we do not desire to be limited to the details thereof as various 10 modifications may occur to a person skilled in the art.

Having now fully described our invention what we claim as new and desire to 15 secure by Letters Patent is:

1. In a lifting jack, a lifting element, a motor operatively connected with said lifting element, means for disconnecting said motor from said lifting element to permit 20 the latter to move downwardly independently of the motor, and means for controlling the downward movement of said lifting element.

2. In a lifting jack, a lifting element, a 25 motor operatively connected with said lifting element, devices to control the downward movement of said lifting element, said devices comprising a brake, and means for disconnecting said motor from said lifting 30 element and for manipulating said brake.

3. In a lifting jack, a lifting element, a 35 motor operatively connected with said lifting element, devices to control the downward movement of said lifting element, said devices comprising means to hold said lifting element normally against downward movement, and a single operating member 40 for disconnecting said motor from said lifting element and for releasing said load to permit it to move downwardly.

4. In a lifting jack, a lifting element, a 45 motor operatively connected with said lifting element, devices to control the downward movement of said lifting element, said devices comprising means to hold the load normally against downward movement, and means to cause said motor to be disconnected from said lifting element before said 50 controlling devices may be actuated to release the lifting element for downward movement.

5. In a lifting jack, a lifting element, a 55 motor operatively connected with said lifting element, devices to control the downward movement of said lifting element, said devices comprising a normally operative brake, and means to cause said motor to be disconnected from said lifting element before said 60 brake is manipulated to permit the downward movement of said lifting element.

6. In a lifting jack, a lifting element, a 65 motor operatively connected with said lifting element, devices to control the downward movement of said lifting element,

said devices comprising a brake, and a single operating member for disconnecting said motor from said lifting element and for manipulating said brake.

7. In a lifting jack, a lifting element, a 70 motor, a clutch to operatively connect said motor with said lifting element, devices to control the downward movement of said lifting element, said devices comprising means to hold said lifting element normally against downward movement, and an operating member operatively connected with said clutch and with said holding means.

8. In a lifting jack, a lifting element, a 75 motor, a clutch to operatively connect said motor with said lifting element, devices to control the downward movement of said lifting element, said devices comprising a normally operative brake, means to release said brake, and an operating member connected with said releasing means and with 80 said clutch.

9. In a lifting jack, a lifting element, a motor, a clutch to operatively connect said motor with said lifting element, devices to 85 control the downward movement of said lifting element, said devices comprising a normally operative brake, and a device operatively connected with said brake and with said clutch, said connections being 90 such that said clutch will be operated before said brake is operated.

10. In a lifting jack, a lifting element, a motor, a clutch to operatively connect said 95 motor with said lifting element, devices to control the downward movement of said lifting element, said devices comprising a normally operative brake, an actuating device for said clutch, and a lost motion connection between said actuating device and 100 said brake, whereby the manipulation of said device will first shift the clutch and then release the brake.

11. In a lifting jack, a lifting element, a 105 motor, a clutch to operatively connect said motor with said lifting element, devices to control the downward movement of said lifting element, said devices comprising a brake drum, brake shoes coöperating with said drum and having intersecting arms, a 110 spring tending to move said arms one toward the other, a rotatable cam arranged between said arms, means for actuating said cam to separate said arms, and an operative connection between said actuating 115 means and said clutch.

12. In a lifting jack, a lifting element, a 120 motor, a clutch to operatively connect said motor with said lifting element, devices to control the downward movement of said lifting element, said devices comprising a 125 brake drum, brake shoes coöperating with said drum and having intersecting arms, a spring tending to move said arms one toward the other, a rotatable stud mounted 130

adjacent to said arms, a cam shaped member carried by said stud and arranged between said arms with its contact surfaces normally out of engagement with the respective arms, a connection between said stud and said clutch, and means for rotating said stud.

13. In a lifting jack, a lifting element, a shaft to operatively connect said lifting element, a motor, a clutch to operatively connect said motor with said shaft, a worm gear rotatably mounted on said shaft,

means for connecting said worm gear with said shaft when the latter rotates in a reverse direction, a worm meshing with said worm gear and adapted to be rotated thereby, a brake connected with said worm, an actuating device for said brake, and an operative connection between said actuating device and said clutch. 15

20 In testimony whereof, we affix our signatures hereto.

CHARLES WM. RIPSCH.
JAMES C. DAWLEY.
